UNITED STATES PATENT OFFICE.

HOWARD G. ALLEN, OF NIAGARA FALLS, NEW YORK, ASSIGNOR TO THE J. L. MORRISON COMPANY, INC., OF NIAGARA FALLS, NEW YORK, A CORPORATION OF NEW YORK.

STAPLING MACHINE.

Application filed August 8, 1921. Serial No. 490,487.

To all whom it may concern:

Be it known that I, HOWARD G. ALLEN, a citizen of the United States, residing in Niagara Falls, in the county of Niagara, 5 State of New York, have invented new and useful Improvements in Stapling Machines, of which the following is a specification.

This invention relates to a stapling machine for driving U shaped wire staples 10 through magazines, boxes, filled-up bags, etc., and relates more particularly to improvements in the type of machine known as the "closed head" stitcher.

One of the objects of the invention is to 15 produce a simple and inexpensive but reliable means of clenching the staple in such a way as to first bend the ends of the staple inwardly by means of a rotary movement of the clenchers and thereafter to compress 20 said staple ends up flat against the material (through which the staple is being driven) by means of a longitudinal, parallel movement of said clenchers. A further object of the invention is to produce a stapling 25 machine construction in which flat, heat-treated clenchers may be used that, in their manufacture, do not have to be perforated for the reception of pivots, studs or the like.

In the accompanying drawings: Figure 1 30 is a fragmentary front elevation of the improved stapling machine showing merely a portion of the bonnet or head and a portion of the clencher mechanism thereof, with a typical piece of work (such as a magazine) 35 shown therebetween prior to the driving of the staple therethrough. Figure 2 is a similar fragmentary elevation but with the parts in a more advanced position and with the staple already driven through the work and 40 partly clenched. Figure 3 is a similar fragmentary elevation with the parts in their final position and with the staple completely clenched. Figure 4 is a top plan view of the clenching mechanism taken on line 4—4, 45 Fig. 2. Figure 5 is a vertical, transverse section through the said clenching mechanism taken on line 5—5, Fig. 1.

Similar characters of reference refer to like parts throughout the several views.

50 In its general organization, this improved stapling machine comprises the usual bonnet or head 10, which is vertically slidably mounted in the upper part of the main frame (not shown) of the machine, and a clencher 55 box 11 which is stationary and is connected

to the lower part of the main frame of the machine. Arranged to slide vertically in a suitable guide 12 of the bonnet 10, is the usual power driver 13 which operates to drive the staple 14 out from its engagement 60 with the aforesaid guide 12 and down through the horizontal folds of the magazine, box, pamphlet, filled-up bag, or other piece of work 15 which is being bound together by said staple 14. Arranged centrally 65 below the said bonnet 10 is the foresaid clencher box 11 which consists of rear plates 16, a front plate 17 and a pair of intermediate spacing plates 19 whose internal edges have an irregular contour, all of said plates 70 being suitably retained in proper relation to each other by stud pins 20 and securely and detachably held together by cap screws 21. Arranged between the front and rear plates 17 and 16, respectively, and within the irregular hollow space intermediate of the spacing plates 19, are loosely and slidably arranged two companion identically-shaped, flat clenchers 22 of bell-crank or L shaped form. Arranged below said clenchers and 75 vertically slidable within the clencher box or casing 11 is a clencher lifter 23 which is connected by means of a rivet 24 or otherwise to a power driven push rod 18, suitably driven by means not shown but in 80 proper synchronism with the rest of the machine, and of course, suitably slidably mounted in the lower part of the main frame of the machine.

In the position of the parts shown in Fig. 90 1, the staple still rests in its guide 12, and the clencher lifter 23 is in its lowermost position, the two clenchers 22 having been pulled down to their lowermost position by the said clencher lifter 23. In this position 95 the outer portions of each of the clenchers is supported by reason of the engagement of the lower face or edge of its pivot head 26 with the upper edge of a pivot ledge 27 formed in each of the spacing plates 19. 100 The first stapling operation of the machine is the power-actuated depression of the head or bonnet 10, and thereafter the power-actuated depression of the driver 13 which causes the U shaped staple 14 to be driven 105 vertically downwardly with its two ends or legs extending vertically downwardly below the lower surface of the material 15 being stapled. The next operation of the machine is the power-actuated elevation 110

2

of the T shaped clencher lifter 23, whose flat upper edge comes in contact with the underfaces of the upper arms of the bell-crank or L shaped, clenchers 22 thereby 5 lifting the same vertically upwardly into the position of Fig. 2. The upper thin edges of the clenchers are provided with longitudinal grooves 30 which engage with and act to center the ends of the staple and 10 operate to bend the same upwardly and inwardly toward each other to the position shown in Fig. 2. This last-mentioned movement of each of the clenchers 22 is a rotary movement about its pivot head 26 as 15 a fulcrum (or approximate center of rotation) said fulcrum being the co-action between the said pivot head 26 and the companion ledge 27 upon which said head rests. In Fig. 2 the two clenchers 22 are shown 20 with the entire length of their upper arms lying flat upon the upper flat surface or end of the clencher lifter 23. The next movement in the staple driving and clenching operation is a straight upward movement 25 of the T shaped clencher lifter 23, the straight upper arm of each of the clenchers continuing to rest flatly upon the flat upper face or edge of the said clencher lifter. Such a movement is rendered possible by 30 a vertically extending clearance notch 33 formed directly above each of the aforementioned pivot ledges 27. In this manner the clenchers 22 are given a direct longitudinally upward movement (not a 35 rotary movement) thereby finally clenching the legs or ends of the staple 13 flat and straight up against the lower flat face of the material being stapled. In this manner the sharp pointed ends of 40 the staple are positively and firmly driven up flush into the body of the material being stapled, so that there is no danger of said staple points becoming caught in a person's clothing, etc.

45 The construction of the entire clenching mechanism is such that the actual clenching operation causes the legs of the staple 14 to be first bent inwardly toward each other and thereafter crushed upwardly with a 50 straight rectilinear motion so that the staple is first properly bent inwardly at the right point and then finally pressed up flat and straight against and into the lower surface of the material 15. The mechanical pos- 55 sitioning of this sequence of operations absolutely prevents the staple from jamming or clogging. Also the fact that a considerable portion of the final clenching operation is a rectilinear movement of the mov- 60 ing parts means that a considerable variation in the thickness of the material and a considerable error of vertical adjustment between the bonnet 10 and the clencher box 11 is possible without in any way affecting 65 the angular movement of the clencher 22

and hence also the bending operation upon the staple legs. It should particularly be noted also that the clenchers, which are made of flat heat treated stamped sheet-metal do not require any perforations either 70 to act as bearings or to act as holes for the reception of the press-fitted pivot studs. It is therefore obvious that these imperforate clenchers can be produced mechanically on a "production" basis and at low 75 cost, and the assembling thereof rendered very simple and definite.

Furthermore, inasmuch as both the clenchers 22, plates 19 and clencher lifter 23 are all made of sheet metal stamped out of sheet 80 metal stock, it follows that all of these plates, are not only easily manufactured, but that they are easily ground down to their proper shape again after the inevitable warping which occurs upon heat treating 85 the same. The action of the clenchers 22 is absolutely positive both their upward and their downward movement being positively actuated by a corresponding movement of the clencher lifter 23. It will furthermore 90 be noticed in Fig. 1, that the pivot head 26, in this position engages with the horizontal shoulder which bounds the upper limit of the clearance notch 33. This absolutely 95 prevents either one of the clenchers from falling inwardly from the position of Fig. 1, even though one of the clenchers should be frictionally or otherwise held up somewhat above its companion clencher in such 100 a manner that the clenchers do not touch each other at all. It should also be noticed that the width of the lower part of the clencher lifter 23 is much less than the width across the extreme upper part of said 105 clencher lifter, so that the same is absolutely prevented from sliding out of or becoming disengaged from the clencher box in the event that the same should be improperly set up in the clenching machine. In other 110 words, when the clencher parts become worn, the manufacturer of the stapling machine can send out as a complete unit, a clencher box 11 together with clenchers 22, plates 19 and clencher lifter 23 disposed therein without any danger of the parts becoming dis- 115 located or falling out of the clencher box.

I claim as my invention:

1. A stapling machine comprising a clencher box having a pair of symmetrically disposed pivot ledges, a vertically movable 120 clencher lifter, and a pair of symmetrically disposed imperforate clenchers each of which is provided on its outer edge with a pivot head which is received within and co-acts with one of said pivot ledges during the 125 first part only of the upward movement of said clencher lifter.

2. A stapling machine comprising a clencher box having a pair of symmetrically disposed pivot ledges and a pair of clear- 130

ance notches located above said pivot ledges, a vertically movable clencher lifter projecting upwardly into said clencher box, and a pair of imperforate clenchers each of which 5 is provided on its outer edge with a pivot head which is received within and coacts with one of said pivot ledges during the first part of the upward movement of said clencher box and traverses the said clear- 10 ance notch during the rest of the upward movement of said clencher box.

3. A stapling machine comprising a clencher box having a pair of symmetrically disposed pivot ledges and a pair of clear-

ance notches located above said pivot ledges 15 and longitudinally in line therewith, a vertically movable clencher lifter projecting upwardly into said clencher box, and a pair of bell crank imperforate clenchers each of which is provided with a pivot head which 20 is adapted to engage with one of the said pivot ledges during the first part only of the movement of said clenchers, and each of which has one of its arms adapted to engage directly with said clencher lifter and 25 its other arm adapted to engage with the staple being driven.

HOWARD G. ALLEN.
